CLAIM

The ornamental design for a display screen or portion thereof with a transitional graphical user interface, as shown and described.

DESCRIPTION

FIG. 1 is a front view of a display screen or portion thereof with a transitional graphical user interface showing a first image in a sequence according to the claimed design; FIG. 2 is a front view of a second image thereof; and, FIG. 3 is front view of a third image thereof.

The appearance of the image transitions sequentially between the images shown in FIGS. 1-3.

The shading in the figures indicate a contrast in appearance. The dash-dot line shows the display screen or portion thereof and forms no part of the claimed design. The broken-line showing of numbers, text and graphic elements forms no part of the claimed design.
